ADJUSTABLE GIRDER

Otto Hinze, Hannover-Kleefeld, Germany

Application February 15, 1957, Serial No. 640,477

Claims priority, application Germany March 2, 1956

2 Claims. (Cl. 189—37)

Girders, particularly formwork girders, which consist of outer and inner girder parts and which can be telescopically increased and reduced in length are known, which comprise a wedge member which is effective between the lower chords of the outer and inner girder parts to locate the girder parts relative to each other. The arrangement of the wedge in an imaginary plane which envelops the outer girder part, however, has given rise to difficulties in operation. Furthermore, the driving of the wedge has caused an impermissible deformation of the inherently parallel lower surfaces of inner and outer girder parts.

The girder, particularly formwork girder, which is proposed according to the invention to eliminate all these disadvantages and which consists of outer and inner girder parts and can be telescopically increased and reduced in length, comprising a wedge member which is effective between the lower chords of the outer and inner girder parts to locate the girder parts relative to each other, is characterized according to the invention in that part of the wedge member extends through the lower chord of the outer girder part. In this connection the term "lower chord" does not refer only to that part of a lattice girder which is stressed in tension under the usual load but also to those parts of a plate girder, e.g. a box girder, which contain the fibre stressed in tension under the usual load conditions.

When the profile of the outer girder part has a lower chord consisting of a closed chord strip, the invention is characterized in that part of the wedge member extends through a slot-like aperture of that lower chord of the outer girder part. Special advantages are obtained thereby that only that part of the wedge member extends through the lower chord of the outer girder part which is effective as a wedge so that in this case a special abutment carried by the outer girder part has to take up the wedge forces. This eliminates the need for special wedge ramps in the outer girder part, which would involve an increase in the clearance between the outer and inner girder parts, resulting in undesirably large differences between the overall heights of the two girder parts; moreover, these wedge ramps deform the inner girder part in the driven condition of the wedge. If that part of the wedge member which is disposed between the lower chords of the outer and inner girder parts is enlarged in width relative to that part of the wedge member which extends through the lower chord of the outer girder part, the dropping of the wedge member through the aperture provided in the lower chord of the outer girder part will be prevented in a simple manner.

The abutment itself consists preferably of a strap which entirely or partly embraces the outer girder part in order to be able to accommodate the taper of the wedge. This is particularly advantageous because that inclination can be achieved without difficulty by welding the strap with an appropriate inclination so that the strap may consist of a simple steel flat or be made from steel flat scrap.

Where stops are provided to prevent the outer and

2

inner girder parts from being pulled entirely apart of the overlap required for carrying strength will always be provided; thus a complete falling apart of the girder is eliminated.

5 Based on the known girder design having C-section outer and inner girder parts, arranged so that the part with respect to the center line of the sections, which is parallel to their webs, the central part of one C-section, which central part is effective as a web, lies opposite to the central part of the other C-section, where the central part is also effective as a web. In that case the wedge member extends partly through a slot in the lower side flange of the outer C-section.

The drawing illustrates a possible embodiment of the invention as applied to a formwork girder.

15 Fig. 1 is a side view of an outer girder part with an inner girder part inserted therein.

Fig. 2 is a similar view showing only the outer girder part.

20 Fig. 3 is a cross-sectional view of this outer girder part.

Fig. 4 is a side view of the inner girder part; whereas

25 Fig. 5 is a cross-sectional view of such an inner girder part.

Fig. 6 is an enlarged side view showing the area where both girder parts overlap.

Fig. 7 is a vertical cross-sectional view taken on the line VII—VII through the formwork girder of Fig. 1, and

Fig. 8 is a vertical cross-sectional view taken on line VIII—VIII of Fig. 1 through the girders.

30 Fig. 9 is a sectional view taken along the lines IX—IX of Fig. 8 and shows the position of the wedge when it is wedged between the strap and the inner girder part; and

35 Fig. 10 is a sectional view similar to that of Fig. 9 but showing the wedge when it is released from its wedging position and resting upon the outer girder part.

As is apparent from the figures the outer girder part comprises a C-section, which consists of the solid central part 1, the flanges 2 and 3 adjoining the central part and effective as upper and lower chords, and the short flanges 4 and 5 continuing said flanges 2 and 3.

40 The C-section of the outer girder part is closed at several points of its length by straps 6, which are slightly outwardly cambered for reasons which will be set forth hereinafter. The somewhat larger closing plate 7 is disposed at the overlap with the inner girder part, which will be described later. As is apparent from Fig. 5 the inner girder part consists also of a C-section, namely,

45 of the central part 8, the flanges 9 and 10 effective as upper and lower chords, and the flange extensions 11 and 12. The C-section of the inner girder part is also bridged by straps 13 at several points. An enlarged closing plate is provided at 14. Opposite to the closing plate 14 the supporting claws 15 are disposed, which are suitably forked.

50 The outer girder part 1, 2, 3, 4, 5 has also such supporting claws 16. The outer and inner girder parts are so related to each other that the solid central part 1 of the outer girder part lies directly opposite to the flange extensions 11, 12 of the inner girder part and that the solid central part 8 of the inner girder part

55 adjoins the inside of the flange extensions 4 and 5 of the outer girder part. The central part 8 of the inner girder part has at 17 a screw arrangement, which in its end position shown at the right in Fig. 1 engages the closing plate 7 in order to establish the largest possible length of the girder.

60 For this reason the straps 6 must be cambered to enable the bypassing of the screw arrangement 17, which would otherwise engage one of these straps if the girder is of insufficient length.

65 The following means are provided for locating the inner and outer girder parts relative to each other:

A wedge member is disposed in the clearance space

18 left between the inner and outer girder parts because the flange 9 of the inner girder part engages the flange 2 of the outer girder part. As is apparent from Fig. 8 that wedge member has the shape of a T. In general, only the part 19 of the wedge member, corresponding to the flange of the T, lies in the clearance space 18, whereas the web of the wedge member corresponding to the web of the T extends through a slot 21 in the lower chord flange of the C-section 1, 2, 3, 4, 5 of the outer girder part. The wedge member 19, 20 has at 22 a wedge nose, to which the forces can be applied which are required for driving the wedge in and out. In accordance therewith the outer boundary face 23 of the web 20 of the wedge has the necessary wedge taper and an abutment conforming to that wedge taper and consisting of the strap 24 transmits the wedge forces occurring to the outer girder part. To this end the strap 24 is welded with a corresponding inclination to the outer girder part, more particularly, it is welded at 25 to the central part 1 and closing plate 7 of the outer girder part.

What is claimed is:

1. A telescoping formwork girder comprising, in combination: at least one outer girder part consisting of a hollow girder, at least one inner girder part longitudinally movable in said outer girder part, one chord of said outer girder part being formed with an elongated slot which extends in the direction of the length of said outer girder part, the ends of said slot being spaced from the ends of said one chord so that said slot is shorter than said one chord, an abutment on said outer girder part, and means for positioning said inner girder part relative to said outer girder part, said positioning means comprising a wedge member of T-shaped cross-section, said wedge member having a wedge web forming the vertical portion of said T-shaped wedge member, said wedge web passing through said elongated slot and having an inclined surface engaging said abutment, and a slide piece forming the upper cross-piece of said T-shaped wedge member, said slide piece being arranged between said one chord of said outer girder part and a chord of said inner girder part and constituting the sole means for preventing passage of the entire wedge member through said slot irrespective of the position which said wedge member occupies relative to said slot while permitting removal of said wedge member

when inward movement of said wedge member into the interior of said outer girder part is not obstructed by said inner girder part.

2. A telescoping formwork girder comprising, in combination: at least one outer girder part consisting of a hollow girder having a C-profile, at least one inner girder part having a C-profile and being longitudinally movable in said outer girder part, said inner and outer girder parts being so positioned with respect to each other that the profiles of both girder parts enclose a hollow space, one leg of said outer girder part being formed with an elongated slot which extends in the direction of the length of said outer girder part, the ends of said slot being spaced from the ends of said one leg so that said slot is shorter than said one leg, an abutment on said outer girder part, and means for positioning said inner girder part relative to said outer girder part, said positioning means comprising a wedge member of T-shaped cross-section, said wedge member having a wedge web forming the vertical portion of said T-shaped wedge member, said wedge web passing through said elongated slot and having an inclined surface engaging said abutment, and a slide piece forming the upper cross-piece of said T-shaped wedge member, said slide piece being arranged between said one leg of said outer girder part and a leg of said inner girder part and constituting the sole means for preventing passage of the entire wedge member through said slot irrespective of the position which said wedge member occupies relative to said slot while permitting removal of said wedge member when inward movement of said wedge member into the interior of said outer girder part is not obstructed by said inner girder part.
